UNITED STATES PATENT OFFICE.

HORACE G. INGRAM, OF JUNIATA, AND SAMUEL GOLDBERG, OF ALTOONA, PENNSYLVANIA.

POWDER-DISPENSING DEVICE.

1,341,174.

Specification of Letters Patent.

Patented May 25, 1920.

Application filed October 16, 1919. Serial No. 331,220.

To all whom it may concern:

Be it known that we, HORACE G. INGRAM, a citizen of the United States, residing at Juniata, county of Blair, and State of Pennsylvania, and SAMUEL GOLDBERG, a citizen of the United States, residing at Altoona, in the county of Blair and State of Pennsylvania, have invented certain new and useful Improvements in Powder-Dispensing Devices; and we do declare the following to be a full, clear, and exact description of the invention, such as will enable others skilled in the art to which it appertains to make and use the same.

15 This invention relates to improvements in powder dispensing devices.

The principal object is to provide a simple and practical device of this character in which the construction is extremely simple 20 and in which the device is formed to dispense an equal quantity every time it is operated.

With the above and other objects in view, the invention consists of certain novel 25 features of construction and the combination and arrangement of parts as will be more fully described and claimed.

We attain these objects by the mechanism illustrated in the accompanying drawings, 30 in which:—

Figure 1 is a vertical sectional view of the device showing the parts in normal position;

Fig. 2 is a section on the line 2—2 of Fig. 1; and,

Fig. 3, a section on the line 3—3 of Fig. 1.

Similar reference numerals designate similar parts throughout the several views.

Reference is now had to the drawing in 40 which a powder container 1 is shown supported on a wall or the like by means of a bracket 2 of any preferred type. The container 1 is provided at its upper end with an inlet opening having a screw cover 3 as illustrated. Positioned adjacent the lower end 45 of the container is a length of metal shaped to form a downwardly tapered wall 4 provided centrally with an elongated outlet opening 5 through which powder passes 50 from the container.

Disposed below the container outlet opening 5 is a flat bottom plate 6, which is flanged and secured to the extreme lower end of the container, said plate being provided with an opening 7 offset from vertical

alignment with the container outlet. Soldered or otherwise secured to the upper face of the bottom plate 6 is a substantially U-shaped frame 8 preferably formed from a single length of wire, said frame partially 60 inclosing the opening in said bottom plate, the arms 9 of said frame forming guides to be engaged by the downturned edges of a plunger plate 10.

The plunger plate 10 is slidable between the bottom of plate 6 and the container outlet 5 and is provided with an opening 11 to align with the container outlet. The metal which is cut to form the opening 11 is bent rearwardly and then cut 65 to form agitating teeth 12 to project in the container through the outlet opening 5. The body of the plunger plate extends rearwardly to form a cover 13 which closes the container outlet when the device is operated.

The container body is provided with an opening in one side, through which projects an operating stem 14 formed of a single length of wire, the inner end of which is 80 bent to form a loop 15, said loop being soldered or otherwise suitably secured to the lower face of said plunger plate. The loop is of a size to surround the opening 11 in the plunger plate and form a pocket in which 85 powder is dropped by gravity from the container when the container outlet and pocket are aligned.

Upon the outer end of the operating stem 14, is mounted a knob or handle 16 and 90 between said knob and the container body is placed a coil spring 17 which surrounds the stem and normally retains the parts in the position shown in Fig. 1.

In operation, the container being filled 95 with a powder such as soap in powdered form, and the parts being arranged as illustrated in Fig. 1 with the handle extending toward the wall, the fingers are pressed against the handle 16 and the pocket containing the powder is pushed forwardly into alignment with the opening in the bottom plate and the powder is delivered there-through into the palm of the hand. It is very apparent that should the powder become packed in the lower end, the agitating 105 fingers may be moved to loosen it.

The openings in the bottom plate, plunger plate and container are preferably of uniform size and shape, and although they 110

are illustrated as being elongated and angular, it is understood that they may be of any preferred shape and size.

From the foregoing description, taken in connection with the accompanying drawings, the construction and operation of the invention will be understood without requiring a more extended explanation.

Various changes in the form, proportion and minor details of construction may be resorted to without departing from the principle or sacrificing any of the advantages of the claimed invention.

We claim:

- 15 1. The combination with a container having a filling opening therein and an outlet opening in its lower end, of a bottom plate disposed below said outlet opening in parallel relation therewith, said plate having an opening offset from the container outlet and of similar contour, a substantially U-shaped wire frame secured to the upper face of said bottom plate, and partially enclosing the opening in said plate, the arms 45 of said frame serving as guides, a flat metal plunger plate slidable between said container outlet and bottom plate, said plunger plate having an opening of the same size as the container outlet and having its end 50 edges turned down over the guides, a wire operating stem extending through one side of said container, a loop formed on the inner end of said stem and secured to the lower face of the plunger plate around its 55 opening to form a powder receiving pocket, the metal cut away to form the opening in said plunger plate being bent upward rearwardly into the container outlet and cut to form agitator fingers, a handle on the outer 60 end of said stem, and a coil spring surrounding the stem between the container and handle to align the pocket with the container outlet, said plunger plate being movable forwardly to discharge powder through 65 the opening in said bottom plate and the rear end portion of said plunger plate serving to close the container outlet while the powder is being discharged from said pocket.
- 20 2. The combination with a container having a filling opening therein and an outlet
- 25
- 30
- 35

opening in its lower end, of a bottom plate disposed below said outlet opening in parallel relation therewith, said plate having an opening offset from the container outlet and of similar contour, a substantially U-shaped wire frame secured to the upper face of said bottom plate, and partially enclosing the opening in said plate, the arms 45 of said frame serving as guides, a flat metal plunger plate slidable between said container outlet and bottom plate, said plunger plate having an opening of the same size as the container outlet and having its end 50 edges turned down over the guides, a wire operating stem extending through one side of said container, a loop formed on the inner end of said stem and secured to the lower face of the plunger plate around its 55 opening to form a powder receiving pocket, the metal cut away to form the opening in said plunger plate being bent upward rearwardly into the container outlet and cut to form agitator fingers, a handle on the outer 60 end of said stem, and a coil spring surrounding the stem between the container and handle to align the pocket with the container outlet, said plunger plate being movable forwardly to discharge powder through 65 the opening in said bottom plate and the rear end portion of said plunger plate serving to close the container outlet while the powder is being discharged from said pocket.

In testimony whereof we have hereunto set our hands.

HORACE G. INGRAM.
SAMUEL GOLDBERG.
